UNITED STATES PATENT OFFICE.

CHARLES R. SPENCER, OF BALTIMORE, MARYLAND, ASSIGNOR TO HENRY F. NEW AND THOMAS W. PATTEN, OF SAME PLACE.

HARNESS.

SPECIFICATION forming part of Letters Patent No. 499,684, dated June 13, 1893.

Application filed January 10, 1893. Serial No. 457,885. (No model.)

To all whom it may concern:

Be it known that I, CHARLES R. SPENCER, of the city of Baltimore and State of Maryland, have invented certain Improvements in 5 Harness, of which the following is a specification.

In the description of the said invention which follows, reference is made to the accompanying drawings forming a part hereof 10 and in which---

Figure 1 is a perspective view of a horse in harness which embodies the present invention. Fig. 2 is an exterior side view of the invention alone, on an enlarged scale. Fig. 3 is a 15 central longitudinal section of Fig. 2. Fig. 4 is a top view of Fig. 2. Fig. 5 is an end view of Fig. 2 looking in the direction indicated by the arrow in that figure.

Referring to the drawings, A A are the 20 shafts of a vehicle. Each shaft is provided with a block B the under side *a* of which is hollowed out. These blocks are secured to the shafts A by means of curved clamps *b* integral with the blocks B the ends of which 25 clamps stand somewhat apart and are connected by bolts *c*. This construction of the clamps admits of the blocks B being connected to shafts differing considerably in size. The upper outer surface of each block B is rounded, 30 see Fig. 5, and at the end nearest the end of the shaft to which it is secured, is a cavity *d* (Fig. 3) extending from the upper or rounded side. Another cavity *e* leads from the under 35 side of the block B, and at the extreme end of the block is a circular depression *f*. The partition *g* between the depression *f* and the cavity *e*, and also the metal *h* between the cavities *e* and *d*, are bored to admit of the reception of the bolt C.

40 D is a spiral spring coiled about the reduced part *i* of the bolt C, and confined endwise between the shoulder *j* and a threaded bush *k* screwed into the partition *g*. By means of the spiral spring D the inner end of the bolt C is pressed against the face *m* of the solid metal *n*, see Fig. 3. The other end of the bolt 45 C has a ring E whereby the bolt may be withdrawn from the cavity *d*.

F is a hollow block, preferably cylindrical, 50 as shown, having a lug *o* adapted to enter the cavity *d*. This lug has a hole *p* through

which the bolt C passes to connect the blocks B and F together. The hollow block F has a head *q* with a central hole *r* therein.

G is a bolt having an eye *a'* to which the 55 trace H leading to the hame I is secured. The trace is shown only in Fig. 1. The other end of the bolt G is threaded and provided with a cylindrical nut *b'* which fits the cylindrical interior of the block F. A pin *c'* in the bolt 60 G prevents the nut *b'* from unscrewing. This pin is inserted through a hole *d'* in the wall of the block.

J and K are spiral springs of different tensions coiled about the bolt G and confined 65 endwise between the head *q* and the nut *b'*. They are separated by a washer *e'* adapted to slide on the bolt. It will be seen that as the bolt G is pulled or drawn by means of the eye *a'*, the lighter spring K is first compressed and 70 after it has reached a certain tension, the other spring J is brought into action.

L is an eye to which the breeching strap M is attached. This eye is connected to the block F by a hook *f'* the point of which is 75 bent over to prevent disconnection.

N is a buckle pivoted to the lugs *g'* on the top of the block F. The tug strap O leading from the saddle, see Fig. 1, is united to this buckle, and the tongue *h'* of the buckle N 80 which is pivoted between the lugs *g'*, has a ring *j'* to which the belly band P, see Fig. 1, is connected. It will be seen that I have dispensed with the long traces; and that the horse pulls directly on the shafts which are 85 moved sidewise as the horse turns without coming in contact with his sides. It will also be understood that the breeching is united to the trace by an elastic connection, and when the horse stands and leans back in the breeching the shafts are slightly raised and do not 90 bear on the saddle.

To disconnect the horse, it is only necessary to withdraw the bolts C until they pass from the lugs *o*, when the shafts are disconnected 95 from the harness and may be lowered, and this is accomplished without any change in the various straps constituting the harness.

I claim as my invention—

1. In combination with the shafts of a vehicle, a block attached to the said shafts, the said block having a cavity and a bolt which 100

passes through the same, another block arranged above the first block and having a lug adapted to pass into the said cavity and be secured therein by means of the bolt aforesaid, a bolt having a trace-eye at one end provided with a spring which is situated in the said block and adapted to be compressed as the trace eye is drawn from the said block, a ring connected to the said block for the breeching, and a tug-buckle pivoted to lugs on the said block having a pivoted tongue and carrying a belly-band ring, substantially as specified.

2. In combination with the shafts of a vehicle, a block attached to the said shafts, the said block having a cavity and a bolt which

passes through the same, another block having a lug adapted to pass into said cavity and be secured therein by means of the bolt aforesaid, a bolt having a trace-eye at one end, 20 springs of differential tension arranged in the said block and adapted to be compressed as the trace-eye is drawn from the block, a ring connected to the block for the breeching, and a tug-buckle pivoted to lugs on the block and 25 having a pivoted tongue carrying a belly-band ring, substantially as described.

CHARLES R. SPENCER.
